LIQUID CONTAINER

Arthur S. Johnson, Beverly, Mass., assignor to
 United Shoe Machinery Corporation, Paterson,
 N. J., a Corporation of New Jersey

Application January 12, 1931. Serial No. 508,087

29 Claims. (Cl. 137—68)

This invention relates to liquid containers for dispensing devices or applying machines and is herein illustrated as embodied in a control valve and locking mechanism for a removable liquid container of the barometric feed type. The present application constitutes a continuation in part of a copending application Serial No. 346,383, filed March 12, 1929, in my name, for improvements in coating machines.

10 Inverted air-tight containers for liquid are utilized in a wide variety of machines and devices, usually for supplying small quantities of liquid to an open receptacle from which said liquid may be removed in small quantities from time to time. A lowering of the level in the open receptacle admits air to the container and allows more liquid to flow out to restore the level and then stops the flow. Such containers are commonly called barometric feed cans or 20 bottles and are found in ink stands, stock watering devices, and water dispensers, as well as in cement applying machines of the type illustrated in the above-mentioned parent application. The containers are filled with liquid while 25 in an upright position and are then inverted with the outlet opening of the container directly above the dispensing receptacle. When the containers are inverted there is considerable danger that the liquid will be spilled unless a control 30 valve is provided for the outlet of the container. Indeed, the same difficulty obtains if it is desired to take the container can away from the machine receptacle before it is empty, as when it is desired to place a cement can in storage in a 35 fireproof vault when the machine is not in use. Provision is sometimes made also for regulating the height of the outlet opening of the container can above the bottom of the receptacle so as to determine the level of the liquid therein.

40 An object of the present invention is to provide, for use with a container inverted on a receptacle and having an outlet valve, an improved locking means for securing the container to the receptacle including mechanism constructed and arranged to prevent removal of the container unless the valve is closed.

45 Valve mechanisms for containers of the type under consideration are commonly constructed so that they cooperate with the receptacle to permit opening and closing the valve after the container can has been inverted in the receptacle as, for example, by rotation of the container can. In the illustrated construction, the container is provided with a turn valve coating 50 with a portion of the receptacle after the con-

tainer is inverted therein so that a rotary movement of the container is effective to open the valve, thereby to deliver liquid to the receptacle. A feature of the invention resides in novel locking mechanism movably mounted on the container and constructed and arranged to secure the container to the receptacle and constructed and arranged to prevent release of the locking means unless the valve is closed.

55 As herein illustrated, the control valve for the liquid container can comprises a turn plate pivoted to the container and notched to cooperate with a portion of the receptacle whereby the valve may be opened after the container has been inverted in the receptacle, by a turning movement of the container. To provide for adjustably supporting the container on the receptacle, there is provided a ring threaded on the container and hence adjustable with respect thereto. As illustrated, also, latches are mounted on this ring for co-operation with the receptacle to hold the inverted container thereon and means are provided for preventing release of these latches unless the valve is in closed position.

60 Inasmuch as turning movement of the container can to open and close the valve is also effective, in the illustrated construction, to turn the container with respect to the supporting ring, it is possible for a careless operator inadvertently to change the relation of the container to the ring and hence to vary the level of the liquid in the receptacle. A further feature of the invention resides in novel locking means effective 65 also to prevent more than a fractional turning movement of the container can with respect to the supporting ring except after a positive release by the user. With this arrangement it is impossible for vibration of the machine to change the adjustment of the container and this 70 adjustment also cannot be affected by accidental displacement of the container without an intended movement of the locking means.

75 These and other features of the invention will now be set forth in detail with reference to the accompanying drawings, in which—

80 Fig. 1 is a vertical section through the valve mechanism at the bottom of the container can showing the co-operating locking mechanism;

85 Figs. 2, 3 and 4 are angular views of this valve and locking mechanism;

90 Figs. 5 and 6 are views looking at the under side of the valve mechanism at the bottom of the inverted container and showing the valve in closed and open position, respectively;

Figs. 7 and 8 are side elevations of a modified form of the locking mechanism showing it in released and clamping position, respectively;

Fig. 9 is a fragmentary view illustrating one of the locking devices moved to another position in which the container is released for rotation to adjust its level;

Fig. 10 is an angular view of this modified locking mechanism detached from the container; and

Fig. 11 is a horizontal section on the line XI—XI of Fig. 8.

The illustrated container 14 is hereinafter referred to as a can, although it is understood that this term is merely descriptive and not exclusive, which is positioned upon an open receptacle 10 of a machine for coating pieces of work with cement.

The inverted can 14 is provided with a threaded neck 20 on which there is adjustably mounted a ring 22 by means of which the container is supported in position upon the rim 24 of a portion of the cement receptacle 10. By adjusting the ring 22 it is possible to vary the position of the lower end of the can with respect to the receptacle and thereby to determine the level of the cement in the receptacle 10. Since the can is full of a liquid such as cement as it is inverted to bring the neck 20 of the can into the receptacle, valve means have been provided temporarily to close the outlet of the can and thereby to prevent spilling the contents. Secured by screws to the lower end of the neck 20 is a plate 26 having an opening 28 (Figs. 2 and 5) which may be closed by means of a rotatable valve plate 30. This valve plate 30 is provided with a similarly shaped opening 32 which may be brought into register with the opening 28, as the turn plate 30 slides over the surface of the plate 26, turning on a pivot screw 33. In its movement around the pivot screw 33, the plate 30 is held in close contact with said plate 26 by means of a flat spring 34, so as thereby to keep the contacting surfaces clean and to prevent leakage. It will be noted that the edge of the turn plate 30 is provided with a notch 36 (Fig. 4) which may be brought into engagement with a rib 38 on the inside of the receptacle as the can is inserted therein. After the notched plate 30 and the rib 38 have been brought into engagement, the valve may be opened by rotating the can to bring the openings 28 and 32 into register, as shown in Fig. 6.

It is desirable to make sure that the operator shall not be able to remove the can while the valve is in open position. Accordingly, the can is provided with latches 40 which are pivotally mounted on the ring 22 and which can be hooked under a ledge 42 on the receptacle 10. It will be noted that a notch 44 (Fig. 2) is provided on the under side of the ring 22 which is brought into engagement with the upper end of the rib 38 (see Fig. 3) as the can is inserted in the receptacle. This prevents rotation of the ring 22 with respect to the receptacle 10 as the can is turned to open the valve or to adjust its position on the receptacle.

Provision is made as above stated for preventing release of the latches when the valve is open. To this end plungers 48 are provided on the latches which are guided in ears 49 on the ring. Springs 51 on the plungers 48 press against the ears 49 normally to hold the latches 40 in engagement with the ledge 42 of the receptacle. The neck 20 of the container is provided with

vertical grooves 46, which are not diametrically opposite, and the plungers 48 are positioned upon the adjacent sides of said latches to enter the grooves 46 in one position of the container can. This position, by reference to the rib 38 of the receptacle 10, is such that the valve plates 26 and 30 are positioned to close the outlet of the can. When the can is turned to open the valve the grooves 46 no longer register with the plungers 48 and it is impossible to release the latches 40 to remove the can.

In the modified construction illustrated in Figs. 7 to 10, inclusive, one of the latches 40 is replaced by a jointed latch 50 the lower portion 52 of which is adapted to engage the ledge 42 of the receptacle 10. The upper end of this lower portion 52 has a groove 54 to receive the lower end of the upper portion 56 which is held therein by means of a pivot pin 58. The inner side of the lower end of the upper part 56 fits rather closely against the bottom of the groove 54 so that inward movement of the upper portion 56 to the position shown in Fig. 7 is effective to tip the lower portion 52 away from the ledge 42. This lower end of the upper portion is also beveled at 60 toward the outside to permit movement of the upper portion 56 independently of the lower portion 52 so as to withdraw from one of two notches or grooves 74 or 76 a plunger 62 somewhat longer than the plunger 48 provided on the other latch. This plunger 62 is secured to the upper portion 56 of the latch 50 by means of a screw 64 passing through a slot 66 in the head of the plunger. A coiled spring 68 is provided as before between the head of the plunger and the ear 49 on the ring 22 through which said plunger is guided. A flat spring 70 secured to a lug 72 on the lower portion 52 of the latch bears against the head of the plunger 62 so as normally to hold the head of said plunger inwardly with respect to the screw 64 in a position in which the inner end of the plunger 62 engages one of the grooves 74, 76 in the neck of the can, thus it will be seen that the plunger 62 is normally held in position to engage the bottom of one of the grooves 74, 76 unless positive force is exerted to force it back and out of the groove.

With the construction illustrated in Figs. 7 to 11, the grooves 74 and 76 are constructed as shown in Fig. 11 and have one substantially radial side and one inclined side. The radial sides are upon adjacent sides of the grooves. By means of this arrangement turning movement of the can through a predetermined fraction of a revolution, here approximately a half turn, to close or open the valve is permitted without manual release of the plunger 62. When the operator desires to turn the can to close the valve, it will not be necessary to press against the upper half 56 of the jointed latch but, upon rotation of the can, the plunger 62 will be cammed out of the groove 76 by the inclined side of said groove and will ride over the threaded surface of the neck into the other groove 74. This arrangement permits the operator to close or open the valve but prevents him from changing the adjustment of the level of the liquid in the receptacle more than that minimum amount which results from a half turn of the can with respect to the ring 22. The design is such, that is to say, the lengths of the plunger 62 and of the slot 66 are such, that when the plunger 62 is not in one of the grooves it will be impossible to move the latch 50 to the position shown in

Fig. 7 so as thereby to release the can from the receptacle, and in only one position of the can, where the groove 74 registers with the plunger 48 and the valve is closed, is it possible to release the other latch 40. As stated above, this arrangement prevents more than fractional rotation of the can with respect to the supporting ring 22 except upon the positive intention of the operator of the machine.

In the use of the invention, an operator will fill the can 14 while it is in upright position and will then turn the plate 30 to bring the openings 28 and 32 out of alinement, to the position shown in Fig. 5. The ring 22 will be adjusted with respect to the neck 20 of the can to determine the level of the liquid in the receptacle 10, and, supposing that the form shown in Figs. 7 to 11 is being used, to this end the upper portion 56 of the latch 50 will be pulled outwardly so as to withdraw the plunger 62 from the grooves 74 and 76 in the neck of the can. The can will then be inverted in position on the receptacle, bringing first the notch 36 and then the notch 44 into engagement with the rib 38. The latches 40 and 50 will be free to snap into engagement with the ledge 42 on the receptacle, and the plunger 62 into the groove 76. After this, the can 14 may be rotated to open the valve. As the valve is opened, the plunger 62 will ride out of the groove 76 and into the groove 74, thereby preventing further rotation in this direction to vary the height adjustment inadvertently. It will be impossible to remove the can from the receptacle without releasing the locking means by pressing inwardly the upper ends of the latches 40 and 50, and this cannot be done unless the can had been rotated in the reverse direction to such a position that the valve is closed and the grooves 74 and 76 are in alinement with the plungers 48 and 62. The form of the invention shown in Figs. 1 to 6 will be used substantially as above described, without having a broken latch 50, with its advantages.

Having thus described my invention, what I claim as new and desire to secure by Letters Patent of the United States is:

1. In combination, a receptacle, a liquid container adapted to be positioned in delivering relation to said receptacle, a rotatable valve to control the passage of liquid from the container to the receptacle, locking means movably mounted on said container for securing the container to the receptacle, and means for preventing the release of said locking means unless the valve is closed.

2. In combination, a receptacle, a liquid container adapted to be positioned on said receptacle and having a turn valve to control the passage of liquid from the container to the receptacle, pivoted means for locking the container to the receptacle, and means interconnecting said pivoted locking means and said valve constructed and arranged to prevent the release of the locking means unless the valve is closed.

3. In combination, a receptacle, a container adapted to be positioned on said receptacle to deliver liquid thereto, a valve for said container to control the passage of liquid constructed and arranged to be opened and closed by turning movement of the container, a latch for locking the container to the receptacle, and means for preventing release of said latch in a plurality of positions of the container with respect to the receptacle.

4. In combination, a receptacle, a liquid container adapted to be placed in inverted position on the receptacle, a turn valve for controlling the passage of liquid from the container to the receptacle constructed and arranged for operation by rotation of the container with respect to the receptacle, latches for holding the container on the receptacle, and means on the container preventing release of the latches when the valve is open.

5. In combination, a receptacle, an inverted liquid container having a neck and adapted to be positioned in said receptacle, a valve for the neck of said container, means movably secured to the neck of the container for locking said container to said receptacle, and means for preventing release movement of said locking means unless the valve is closed.

6. In combination, a receptacle, a liquid container having a neck adapted to be inverted in said receptacle, a turn valve on the neck of said container having a notched periphery, and a rib within said receptacle adapted to co-operate with the notch in the periphery of said valve to the end that said valve may be opened by turning the container after it has been placed in inverted position with its neck within the receptacle.

7. In combination, a receptacle, a liquid container having a neck adapted to be inverted in said receptacle, a ring adjustably mounted on the neck of said container, locking means secured to said ring adapted to engage said receptacle to hold the container therein, and means co-operating with said container and said locking means preventing operation of the locking means in a plurality of positions of the container with respect to said ring.

8. In combination, a receptacle, a liquid container having a neck adapted to be inverted in said receptacle, a valve for the neck of said container constructed and arranged to be opened by turning movement of the container with respect to the receptacle, movable locking means for holding the container on the receptacle, and means for preventing movement of said locking means in a plurality of positions of rotation of the container thereby to prevent removal of the container when the valve is in open position.

9. In combination, a receptacle, a liquid container having a neck adapted to be inverted in said receptacle, a ring secured to the neck of said container, a latch extending between said ring and said receptacle to hold the container on the receptacle, the neck of said container having a groove, and means for preventing operation of said latch until said container is rotated to bring said groove into a predetermined position.

10. In combination, a receptacle, a liquid container having a neck adapted to be inverted in said receptacle, said receptacle having an internal rib, the neck of said container being provided with a valve having a rotatable member provided with a notched edge to enable the valve to engage the rib in the receptacle, locking means comprising a ring rotatably mounted on the neck of said container, said ring having a notch to engage the rib in the receptacle, and means co-operating with said container and said receptacle constructed and arranged to lock the container to the receptacle in a plurality of positions of rotation of the container.

11. In combination, a receptacle, a liquid container adapted to be inverted in said receptacle, a valve for said container constructed and ar-

- ranged to be opened and closed by rotation of the container with respect to the receptacle when in inverted position therein, locking means for securing the container to the receptacle comprising pivoted latches, a neck on said container having grooves therein which are offset from a diameter thereof, and plungers on said latches adapted to enter said grooves to allow the release of the latches in one position of the container with respect to the latches. 80
12. In combination, a receptacle, a liquid container adapted to be inverted in said receptacle, a supporting ring threaded on said container adapted to rest on said receptacle, said container having a groove, a two-part latch on said ring, the lower part of said latch being arranged to hold the container on the receptacle, means on the upper part of the latch for preventing a release of the lower part of the latch until said groove is brought into register therewith, and a spring permitting movement of the upper part of the latch to withdraw said means from said groove thereby to permit turning movement of the container with respect to the ring. 85
13. In combination, a receptacle, a liquid container having a neck adapted to be inverted in said receptacle and provided with a valve, means adjustable secured to the neck of said container for supporting the container on the receptacle, a latch for holding said container on said receptacle constructed and arranged to prevent detachment of the receptacle when said valve is open, and means on said latch for preventing accidental change of the adjustment of said supporting means with respect to said container. 90
14. In combination, a receptacle, a liquid container inverted therein, a supporting ring threaded on said container adapted to support the container on the receptacle, and releasable means for controlling the relative rotation of said ring and said container. 95
15. In combination, a receptacle, a liquid container adapted to be inverted in said receptacle and provided with a valve constructed and arranged to be opened by turning movement of the container with respect to the receptacle, and releasable means for limiting the turning movement of the container with respect to the receptacle to a predetermined fraction of a revolution. 100
16. In combination, a liquid container adapted to be inverted in said receptacle and provided with a valve constructed and arranged to be opened by turning movement of the container with respect to the receptacle, releasable means for limiting the turning movement of the container with respect to the receptacle to a predetermined fraction of a revolution, and means associated therewith for locking the container to the receptacle when the valve is open. 105
17. In combination, a receptacle, a liquid container adapted to be inverted in said receptacle and provided with a valve, a latch for holding said container on said receptacle releasable only when said valve is closed, and means adjustably secured to the container for determining the height of the valve opening above the bottom of the container, said latch being provided with means for preventing accidental change of said adjustably secured means. 110
18. In combination, a receptacle, a liquid container adapted to be inverted in said receptacle and provided with a valve, means threaded on said container for supporting it in the receptacle, and a releasable latch for preventing turning movement of said supporting means with respect to the container for more than a predetermined fraction of a revolution while permitting movement sufficient to open and to close the valve. 115
19. In combination, a receptacle, a liquid container adapted to be inverted in said receptacle, a ring threaded on said container for supporting the outlet of the container a predetermined dis- 120
- tance above the bottom of the receptacle, the sides of said container being provided with grooves having straight sides and inclined sides, and a releasable plunger spring pressed into engagement with said container at the bottom of one of said grooves constructed and arranged thereby to limit the turning movement of the container to the distance between said grooves. 125
20. In combination, a receptacle, a liquid container adapted to be inverted in said receptacle, a supporting ring threaded on said container adapted to rest on said receptacle, said container having a groove, a two-part latch on said ring, the lower part of said latch being arranged to hold the container on the receptacle, means on the upper part of the latch for preventing a release of the lower part of the latch until said groove is brought into register therewith, and a spring permitting movement of the upper part of the latch to withdraw said means from said groove thereby to permit turning movement of the container with respect to the ring. 130
21. In combination, a receptacle, a liquid container adapted to be inverted in said receptacle and having a turn valve to control the passage of liquid from the container to the receptacle, means for locking the container to the receptacle, means interconnecting said locking means and said valve constructed and arranged to prevent the release of the locking means unless the valve is closed, means threaded on said container for supporting it in the receptacle, and means associated with said locking means for preventing turning movement of said supporting means with respect to the container for more than a predetermined fraction of a revolution thereby to prevent accidental relative movement of the container and its supporting means and consequent variation of the height of the container with respect to the receptacle. 135
22. In combination, a receptacle, a liquid container adapted to be inverted in said receptacle and provided with a valve to control the passage of liquid arranged to be opened by turning movement of the container with respect to the receptacle, adjustable supporting means threaded on said container and resting on said receptacle, releasable latches for locking the container to the receptacle, and means for preventing release of the locking means when the valve is open and for preventing turning movement of the container with respect to the receptacle through more than a predetermined fraction of a revolution. 140
23. In combination, a receptacle, a liquid container adapted to be inverted in said receptacle and having a threaded connection determining the height of the outlet of the container above the bottom of the receptacle, the side of said container being recessed to provide substantially radial sides and sloping sides, the radial sides being adjacent to one another, and a releasable plunger spring pressed into engagement with said container thereby to limit movement of the container to a degree determined by contact of said plunger with one radial side or the other radial side alternatively. 145
24. In combination, a receptacle, a liquid container adapted to be inverted in said receptacle and having a threaded connection determining the height of the outlet of the container above the bottom of the receptacle, the sides of said container being provided with grooves having substantially radial sides and sloping sides, the radial sides being adjacent to one another, a 150

- releasable plunger spring pressed into engagement with said container thereby to limit movement of the container to a degree determined by contact of said plunger with one radial side 5 or the other radial side alternatively, and a valve at the outlet of said container constructed and arranged to be opened and closed by turning movement of the container with respect to the receptacle, the degree of turning movement permitted by the said plunger being sufficient to open and close the valve. 10
25. In combination, a receptacle, a liquid container adapted to be inverted in said receptacle and having a threaded neck carrying a turn valve, adjustable supporting means threaded on said neck and resting on said receptacle, a releasable locking latch mounted on said supporting means and locking the container to the receptacle, and means for preventing releasing movement of said latch when the valve is open while permitting a predetermined amount of movement of the container to open and close the valve. 15
20. In combination, a receptacle, a liquid container adapted to be inverted in said receptacle and having a threaded neck carrying a turn valve, adjustable supporting means threaded on said neck and resting on said receptacle, a releasable locking latch for locking the container to the receptacle mounted on one side of said supporting means, a releasable two-part locking latch mounted on another side of said supporting means, and means cooperating with said latches to prevent release of the same while permitting a predetermined amount of rotation 25 of the container to open and close the valve. 30
27. In combination, a receptacle, a liquid container adapted to be inverted in said receptacle and having a threaded neck carrying a turn valve, adjustable supporting means threaded on said neck and resting on said receptacle, a releasable locking latch mounted on said supporting means and locking the container to the receptacle, and means for preventing releasing movement of said latch when the valve is open while permitting a predetermined amount of movement of the container to open and close the valve. 35
28. In combination, a receptacle, a liquid container having a neck adapted to be positioned for rotary movement in said receptacle and provided with a turn valve, supporting means adjustably mounted on said container for supporting the container on the receptacle, releasable latches mounted on said supporting means for locking the container to the receptacle, and means constructed and arranged to prevent release of said latches unless the valve is closed while permitting sufficient rotary movement of the container with respect to the receptacle to open and close the valve. 40
29. In combination, a receptacle, a liquid container inverted thereon, a ring threaded on said container adapted to rest on the receptacle to support the container thereon, and a rotatable valve to control the passage of liquid from said container to the receptacle constructed and arranged to be opened by relative fractional turning movement of the container with respect to the receptacle whereby the height of the valve opening above the bottom of the receptacle is substantially independent of the valve mechanism. 45

CERTIFICATE OF CORRECTION.

Patent No. 1,922,297.

August 15, 1933.

ARTHUR S. JOHNSON.

It is hereby certified that error appears in the printed specification of the above numbered patent requiring correction as follows: Page 2, line 119, for ", thus" read . Thus; page 3, line 86, claim 5, after "inverted" insert barometric; and page 4, line 20, claim 13, for "adjustable" read adjustably; and that the said Letters Patent should be read with these corrections therein that the same may conform to the record of the case in the Patent Office.

Signed and sealed this 14th day of November, A. D. 1933.

E. M. Hopkins

(Seal)

Acting Commissioner of Patents.
